UNITED STATES PATENT OFFICE

2,283,079

CAKE HOLDER

Henry J. McDermott, Prospect Park, Pa., assignor
to American Viscose Corporation, Wilmington,
Del., a corporation of Delaware

Application July 2, 1940, Serial No. 343,538

2 Claims. (Cl. 242—128)

This invention relates to improvements in apparatus for supporting and unwinding a yarn package or the like.

In the manufacture and finishing of various types of yarn, it is often desirable to subject the yarn to a liquid treatment while in package form. For instance, in one method of manufacture of rayon by the viscose process, the rayon is collected in a spinning box in an annular formation, which is called a cake. The rayon cake is subjected to various liquid treatments, such as washing, desulphurizing and bleaching. Also, it is often desirable to subject finished rayon or other yarn in package form to liquid treatment such as dyeing. After the liquid treatment the yarn is generally unwound from the package and formed into skeins or wound on bobbins or cones. The liquid treatment of the yarn package tends to disarrange and tangle the yarn which makes the unwinding operation difficult.

The principal object of this invention is to provide an improved means for supporting and unwinding a yarn package or the like that has been subjected to a liquid treatment.

Other objects and advantages of the invention will be apparent from the following description and accompanying drawings in which a preferred embodiment of the invention is shown.

In the drawings:

Figure 1 is a view of an embodiment of the invention applied to a winding machine.

Figure 2 is a vertical sectional view of the embodiment of the invention in Figure 1.

Figure 3 is a view of the embodiment of the invention in Figure 1 shown with parts broken away.

While the invention is shown and described as applied to a winding machine it is to be understood that it may be used with any other type of machine where yarn is unwound from a package.

In the drawings, reference character 1 indicates yarn being withdrawn from the package 2 mounted on the package supporting means generally indicated by reference character 3. The yarn is directed to the driven take-up bobbin 4 by the guide means 5 carried by the traverse rail 6. The package supporting means comprises the hollow shaft 7 on which are mounted the flange or base 9, the rotatable flange 10, and the package gripping means 11. The shaft is supported on the frame member 8. The position of the flange 9 may be adjusted along the shaft by means of the clamping member 12. The rotatable flange is journaled on the shaft and is readily removable therefrom. The portion of the rotatable flange adjacent its perimeter slopes outwardly and the edge is smooth. The package

engaging means 11 are loops of spring steel or other resilient material fixed to the head 13 which is secured to the shaft. The position of the head may also be adjusted along the shaft. 5 In order to reduce the tension on the yarn the rotatable flange may be rotated. The means for rotating the flange comprises the drive shaft 14 extending through the hollow shaft and having a head portion 15 which frictionally engages the member 16 on the rotatable flange. The drive shaft 14 is rotated by an air motor or other means which is not shown.

In placing a yarn package on the package supporting means the rotatable flange is first 15 removed. The yarn package, into which has been inserted a celluloid collar 18 or other annular reinforcing means, is passed over the shaft and the gripping members and is placed on the flange 9. The gripping members tend to spring 20 outwardly and thereby retain the package in position. If the yarn package is wrapped in a protected cover, as indicated by reference character 17 in Figure 2, the lower end of the cover is drawn over the flange 9 and the upper end is drawn inwardly and downwardly over the reinforcing means inside the package. The rotatable flange is then replaced on the shaft and the yarn is withdrawn from the package over its edge.

30 While a preferred embodiment of the invention has been shown it is to be understood that changes and variations may be made without departing from the spirit and scope of the invention as defined by the appended claims.

35 What I claim is:

1. Means for supporting and unwinding a yarn package comprising a shaft, a yarn package supporting base mounted on the shaft, a hub mounted on the shaft and spaced from the base, yarn 40 package retaining means comprising loops of spring material attached to the hub and adapted to engage a yarn package supported on the base, and a member mounted on the shaft over the edge of which yarn may be withdrawn from a yarn package supported on the base.

2. Means for supporting and unwinding a yarn package comprising a shaft, a yarn package supporting base mounted on the shaft, a hub mounted on the shaft and spaced from the base, said hub being adjustable along the shaft, yarn package retaining means comprising loops of spring material attached to the hub and adapted to engage a yarn package supported on the base, and a member mounted on the shaft over the edge of which yarn may be withdrawn from a yarn package supported on the base.

HENRY J. McDERMOTT.
